Attorney

UNITED STATES PATENT OFFICE.

JAMES H. JONES, OF ETOWAH, TENNESSEE.

PIPE-JACK.

1,305,805.

Specification of Letters Patent.

Patented June 3, 1919.

Application filed January 30, 1919. Serial No. 274,119.

To all whom it may concern:

Be it known that I, JAMES H. JONES, a citizen of the United States, residing at Etowah, in the county of McMinn and State of Tennessee, have invented certain new and useful Improvements in Pipe-Jacks, of which the following is a specification.

The present invention comprehends generally improvements in that class of inventions known as pushing and pulling and more particularly relates to an improved pipe jack.

It is the principal object of this invention to provide a device of the above mentioned character designed to be used for separating pump injector and boiler check connections and for other pipe work, the component parts being of novel construction and arranged so as to be easily adjusted relative to each other.

More particularly this invention consists in the provision of a device of the above mentioned character embodying an attaching and supporting clamping bracket for effectively supporting the operating parts, the bracket being of novel construction and is capable of being quickly applied and detached.

It is a more specific object of this invention to provide a device of the above mentioned character wherein the coacting adjusting members are of improved construction and are mounted in the attaching and supporting bracket in a manner so that they can be conveniently adjusted for accomplishing the desired purpose.

Among the other aims and objects of this invention may be recited the provision of a device of the above mentioned character wherein the number of parts are few, the construction simple, the cost of production low and the efficiency high.

Other objects, as well as the nature, characteristic features and scope of this invention will be more readily apparent from the following description taken in connection with the accompanying drawings and pointed out in the claims, forming a part of this specification.

The invention is clearly illustrated in the accompanying drawings, in which:

Figure 1 is a side elevation showing the device applied in an operative position,

Fig. 2 is an enlarged fragmentary longitudinal sectional detail,

Fig. 3 is a cross sectional view taken

through the device showing particularly the attaching and supporting bracket.

Fig. 4 is an enlarged sectional detail showing the means for connecting the clamping brackets together, and

Fig. 5 is a detail in plan of the head of the jack.

Similar characters of reference are employed in all of the above described views, to indicate corresponding parts.

Referring now, more particularly, to the accompanying drawings, there is provided the improved attaching and supporting clamping brackets generally indicated by the numeral 1, which in the present instance preferably consist of coacting sections 2 and 3. The section 2 is formed of metal and has a portion bent arcuate or semi-circular to form a clamping jaw while a straight portion 4 continues therefrom and terminates in a tubular supporting portion 5 for a purpose which will appear. The straight portion 4 is formed with a transverse opening or slot while projecting from the straight portion at the ends of the slot are ears 6 also for a purpose to appear. Another relatively straight portion 7 continues from the outer end of the jaw and is formed with an opening. The other section 3 of the bracket is bent to provide a semi-circular jaw contacting with the jaw on the section 2 and is formed at its inner terminal with an offset hinged ear 8 which is designed to be passed through the opening or slot in the straight portion 4 and arranged in alinement with the ears 6 while passed through the alining ears 6 is a bolt 9 which serves as a means for pivotally connecting the sections 2 and 3 together, the bolt being retained in position desirably through the instrumentality of a nut 10. The jaw of the section 3 terminates in a relatively straight portion 11 and is designed to be disposed opposite to and in spaced parallel relation with the straight portion 7 of the section 2 subsequent to the passing of the jaws about a pipe section 12 or other piece of work, being finally engaged by a screw or other retainer 13 which acts to clamp the jaws in frictional engagement with the section or pipe 12.

With a view toward providing the improved coacting adjusting members, there is employed a sleeve member 14 which is rotatably receivable in the tubular receiving and supporting body 5, the inner surface being provided with screw threads 15 for a pur-

pose which will presently appear while this sleeve member is formed at one end with a head 16 the outer surface of which is desirably octagonal as at 17 and each flat face 5 is formed with an inwardly extending socket 18 adapted to receive an adjusting wrench (not shown) for a purpose which will presently appear. Adjustably mounted within the sleeve member 14 is a correspondingly 10 exteriorly threaded screw member 19, one end of which is formed with a head 20 the flat faces of which are provided with wrench engaging sockets 21 to facilitate the adjustment of the screw member. In addition the 15 outer edge of the head 20 is roughened as at 22 to facilitate the anchoring of the screw member against the casing from which the pipe section 12 is being removed. The opposite end of the screw member is formed 20 with an inwardly extending circular socket 24 designed to receive the stem 25 of the pointed swivel head 26. A portion of the head is formed with a plurality of flat faces 27 each of which is in turn formed with 25 an inwardly extending wrench engaging socket 28.

In use, assuming that the clamping jaws of the sections 2 and 3 are applied about the 30 pipe section 12 and that the head 20 of the screw member 19 is arranged against the casing 23 with the screw member in turn engaged in the sleeve member in the receiving body as shown in Fig. 1, to cause a separation of the section 12 from the casing 23 35 subsequent to loosening the connecting member. A suitable wrench (not shown) is employed and is engaged with the socket 18 in the head 17 to rotate the sleeve member in the receiving body 5, this causing the sleeve member to work outwardly on the screw 40 from the head 20 and inasmuch as the head 17 abuts the body 5 and the clamp 1 is engaged on the section 12, the latter will be moved away from the casing, the knurled 45 or roughened face 22 of the head 20 of the screw member preventing a rotation of the member 19 during this operation. When the parts are arranged as in Fig. 2 the pointed swiveled head 26 is engaged for instance 50 against a casing or other piece of work (not shown) while the clamp as usual is applied about a pipe section 12 and when the parts are arranged in this position a wrench (not shown) is adapted to be engaged with the 55 socketed head 20 to rotate the screw member 19 while another wrench (not shown) may be engaged in the socket 18 to prevent the rotation of the sleeve member 16 and cause the latter to move outwardly or away from 60 the swivel head during the rotation of the screw member, this action also causing a separation of the pipe section 12 from the casing (not shown).

Although there has been particularly described the two uses and operations of the 65 invention, it is desired to be understood that the present combination and arrangement is not limited to these specific uses but may be used by plumbers, mechanics, et cetera, for pipe work and work of other characters. 70

It is believed in view of the foregoing description that a further detailed description of the operation of the invention is entirely unnecessary. Likewise, it is believed that the advantages of the invention will be 75 readily apparent.

Still further embodiments than those herein especially defined may be resorted to as conditions or preference may dictate, as may be in keeping with the hereto appended 80 claims.

Having thus fully described the invention, what is claimed as new and desired to be secured by Letters Patent, is:—

1. A pipe jack of the character described 85 including a sectional attaching and supporting clamping bracket, a tubular receiving body formed thereon, an interiorly threaded sleeve member arranged in the tubular body, a head on one end of said sleeve member 90 and designed for abutting engagement with one end of the body and also provided with a plurality of sockets, a screw member operatively arranged in said sleeve member, one end of the screw member being provided 95 with a socket, a pointed head having a stem swiveled in said socket, and another head integral with the opposite end of the screw member and provided with a plurality of 100 sockets.

2. A pipe jack of the character described including an attaching and supporting bracket composed of a pair of metallic sections, other sections being bent to form an arcuate jaw, a straight portion continuing 105 from one end of the jaw and having an opening therein, a tubular receiving body continuing from the straight portion, ears projecting from the straight portion at the ends of the opening, another straight portion continuing from the opposite end of the jaw, the other section being bent to form 110 an arcuate jaw, an offset hinged ear formed at one end of the last mentioned jaw, pivotal means engaging the ears for pivoting the sections together, a straight portion formed at the outer terminal of the last mentioned jaw, means detachably engaging the straight portions with the outer terminals of the jaws 115 for releasably holding the jaws in clamping relation, and coacting adjusting members one of which is operably mounted in the tubular body. 120

In testimony whereof, I affix my signature hereto.

JAMES H. JONES.
